(57) **CLAIM**

The ornamental design for a probe for nasal aspirators, as shown and described.

DESCRIPTION

FIG. 1 is a perspective view of a probe for nasal aspirators embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view thereof taken along lines 8-8 of FIG. 4;

FIG. 9 is an exploded left side elevation view thereof;

FIG. 10 is a cross-sectional view thereof taken along lines 10-10 of FIG. 9;

FIG. 11 is a top exploded perspective view thereof;

FIG. 12 is a bottom exploded perspective view thereof;

FIG. 13 is a top perspective view thereof, showing the article in use; and,

FIG. 14 is an exploded perspective view thereof, showing the article in use.

The broken lines shown in the figures depict portions of the probe for nasal aspirators that form no part of the claimed design.
